UNITED STATES PATENT OFFICE.

FREDERICK F. CLARKE, OF FRANKLIN, PENNSYLVANIA, ASSIGNEE TO COLBURN MACHINE TOOL COMPANY, OF FRANKLIN, PENNSYLVANIA, A CORPORATION OF PENNSYLVANIA.

TURRET CONSTRUCTION FOR VERTICAL BORING AND TURNING MILLS.

1,188,042.

Specification of Letters Patent. Patented June 20, 1916.

Application filed December 3, 1914, Serial No. 875,833. Renewed May 10, 1916. Serial No. 96,711.

To all whom it may concern:

Be it known that I, FREDERICK F. CLARKE, citizen of the United States, residing at Franklin, in the county of Venango and State of Pennsylvania, have invented certain new and useful Improvements in Turret Construction for Vertical Boring and Turning Mills, of which the following is a specification.

10 The object, construction and operation of my improved turret for boring and turning-mills, are herein set forth with sufficient clearness to enable those skilled in the art of boring-mill construction, to make and use 15 the same.

The objects of this invention are, to provide an improved turret construction for vertical, boring and turning mills, the revolving mechanism for which will be more 20 easy of access and operation than those commonly employed, and in addition thereto to provide the turret with a take-up device whereby any possible play or looseness, due to the revolvability of said turret or any 25 wear occurring therein, may be taken up and positively eliminated, when the turret is locked for operation. The construction whereby I attain said objects, is clearly shown in the drawings, the various figures 30 of which are as follows:

Figure 1 is a central, vertical section of my improved turret and slide. Fig. 2 is an elevation of the rear face of the turret, a portion being broken away to expose the 35 pinion which revolves the turret. Fig. 3 is a front elevation of the turret-slide, with the turret removed. Fig. 4 is a central, vertical section of the turret, removed from the slide. Fig. 5 is a central, vertical section of 40 the turret-slide with the turret removed.

In Fig. 1 and Fig. 4 I have shown but one tool-socket in the turret, but in actual practice, five are provided. Neither the number of sockets, however, nor the precise 45 construction of the turret as it pertains to said sockets, are material to the embodiment of this invention.

The embodiment of my inventive idea as here illustrated, and which, as previously 50 stated, relates to revolving and take-up mechanisms, is substantially as follows:—The mount for the turret or turret-slide—Fig. 3 and Fig. 5—is provided with an annular seat 1 for the reception of the

turret,—Fig. 2 and Fig. 4,—and upon which 55 seat, the face 2 of said turret seats: Said turret is also provided with a rearwardly-projecting, integral, annular feature, hub 3, which revolvably occupies the opening 4 in said slide. To the rearward face of said 60 hub 3 is rigidly secured a take-up ring 5. To the turret-slide at the rear of the opening 4, is rigidly secured a base-plate 6, and positioned centrally in the same and extending therethrough, is a take-up screw 7, having an actuating-arm 8. Mounted upon the screw 7, is a take-up plate 9, which is centrally screw-threaded for the reception and engagement of the thread of said take-up screw. Passing through the flange of said 70 plate are dowel-screws 10 which are secured in said flange by means of its screw-threaded portion; the inner end or point of each of said screws is formed into a dowel 11, which enters a socket provided therefor in the base-plate; there being a number of said sockets 75 as shown at 11' in Fig. 3, which are for the purpose of permitting adjustments of said plate 10.

By reference to Fig. 1 it will be readily 80 noted that the inner face of the take-up plate 9 bears against the adjacent face of the take-up ring 5 of the turret, and that, by turning the take-up screw 7 slightly, the 85 turret may be drawn firmly and securely to its seat, whereby any looseness due to the revolvability of the turret or any wear resulting from revolving same may be taken up, thus causing said turret to have absolute rigidity of bearing and accuracy of 90 operation at all times. To the actuating-arm 8 of screw 7 is secured one end of the actuating-rod 12; the other end of said rod being attached to a knuckle 13 that is operated by a lever 14.

When the turret is to be revolved, it is first unlocked, then lever 14 is manually actuated so as to turn the screw 8 and cause an outward movement or disengagement of the take-up plate 9; said outward movement 95 releases ring 5 from the inward pressure and take-up action of said plate against ring 5 and leaves the turret free to be revolved, by means which will presently be described. The dowel-pins 11 permit the outward-and-inward movement of the take-up plate 9, but prevent the turning of same when screw 7 is actuated. If, at any time, on account of 100 105

wear, it is found desirable to readjust the take-up plate, this may be done by removing screws 10 and turning said plate so that the dowels 11 may be reinserted into 5 the supplementary adjusting-holes 11'.

The usual form of locking-device is provided for the turret, and consists of a vertically, longitudinally-movable lock 15, actuated to the unlocking position by a lever 10 20, and to the locking position by means of the spring 21, which bears against the upper end of said lock. Secured to the inner face of the turret, is a locking-ring 15' which is provided with the lock-seats 15'', which seats 15 correspond in number to the number of tool-sockets 16 contained in the turret. For the purpose of revolving said turret, or turning same so that the tools in said sockets 16 may be successively brought into the operative position, I provide the following construction, 20 25 which I believe to be new in the form and adaptation here employed:—At the outer edge of the turret-opening 4 in the turret-slide, is secured an annular rack or intermeshing-gear 17. The turret is provided with a revoluble pinion 17', which is secured to a shaft 18 that passes revolubly through the turret and is provided upon its outer end with a crank 19. By this means a convenient 30 35 and easily-actuated revolving-mechanism is provided, which is within easy reach of the operator from his position in front of the machine.

When the turret is to be revolved, or 35 40 turned to bring the tools contained in the respective sockets successively into the operative position, said take-up is first released by the actuation of lever 14; lock 15 is then disengaged from the locking-seat in ring 15', crank 19 is then manipulated, and as the adjacent seat 15'' comes into lock-receiving position, said lock is thrust into the same by the action of spring 20, which bears against the upper end of said lock, thus 45 50 locking the turret in position. The take-up device is then set by the actuation of said lever 14, whereby the turret is made as rigid and firm as though it were an integral portion of the slide which carries the same, thus complete accuracy of alinement and operation is secured.

I claim the following:

1. A turret construction for boring mills consisting of a revoluble turret provided 55 with suitable tool-sockets and having the

rear face thereof formed into a seat, hub formed upon said face and positioned centrally thereof, a pinion mounted in said turret and arranged to revolve the same, means operable to revolve said pinion, a 60 clamping ring secured to the inner end of said hub, in combination with a mount for said turret provided with a seating face adapted for the reception of the seating face of said turret, and provided also with 65 an opening for the reception of said hub, an internal gear positioned within said opening adapted to be engaged by said pinion, a base-plate rigidly secured to said mount at the rear of said opening, a screw revolubly mounted in said plate with its threaded end projecting outwardly therefrom, means operable to actuate said screw, and a clamping-plate engaged by said screw and in turn 70 75 engaging said clamping-ring, for the purpose of rigidly clamping said turret to said mount.

2. A turret-construction for boring-mills, consisting of a revoluble turret provided with suitable tool-sockets, and having the 80 rear face thereof formed into a seat, a hub formed upon said face and positioned centrally thereof, a locking-ring secured to said face, a pinion mounted in said turret and arranged to revolve the same, means operable to revolve said pinion, a clamping-ring secured to the inner end of said hub, in combination with a mount for said turret provided with a seating-face adapted for the 85 90 reception of the seating-face of said turret and provided also with an opening for the reception of said hub, a locking-device adapted to engage said locking-ring, an internal-gear positioned within said opening, adapted to be engaged by said pinion, a 95 base-plate rigidly secured to said mount at the rear of said opening, a screw revolubly mounted in said plate with its threaded end projecting outwardly therefrom, means operable to actuate said screw, and a clamping-plate engaged by said screw, and in turn 100 105 engaging said clamping-ring, for the purpose of rigidly clamping said turret to said mount.

In testimony whereof I affix my signature 105 in presence of two witnesses.

FREDERICK F. CLARKE.
